UNITED STATES PATENT OFFICE.

JOSEPH FURRER, OF TOLEDO, OHIO.

ARTIFICIAL LEG.

SPECIFICATION forming part of Letters Patent No. 292,800, dated February 5, 1884.

Application filed July 14, 1883. (No model.)

To all whom it may concern:

Be it known that I, JOSEPH FURRER, a citizen of the United States, residing at Toledo, in the county of Lucas and State of Ohio, have 5 invented certain new and useful Improvements in Artificial Limbs, of which the following is a specification, reference being had therein to the accompanying drawings.

This invention relates to certain new and 10 useful improvements in artificial limbs; and it has for its object to provide means for making a perfectly flexible connection between the limb and the foot at the ankle joint; and with this in view my invention consists, es- 15 sentially, in providing the artificial foot with journals or supports, and the adjoining sec- 20 tion of the limb with a cup-shaped socket hav- 25 ing a shaft adapted to fit and rock in the said journals. Springs are interposed between the foot and lugs extending forwardly and rear- 30 wardly from the socket, and a yielding brace 35 is also connected, respectively, to the foot and the limb-socket, so as to additionally unite the parts together, all the peculiarities of which 40 will hereinafter more fully appear.

In the accompanying drawings, forming a 45 part of this specification, and on which like reference-letters indicate corresponding parts, Figure 1 is a vertical sectional view taken 50 through the foot and the socket, showing the relative arrangement of the several devices; and Fig. 2, an end elevation, looking from the back.

The letter A indicates the improved artifi- 55 cial foot, the same being constructed, prefer- 60 ably, of wood, and at the heel it is provided with a cushion or spring, a, the object of which is to soften the tread and prevent jarring. The rear portion of said foot is cut away, as indi- 65 cated, and upon said portion is mounted and 70 rigidly secured the journal-blocks B, the base- 75 piece of which extends forwardly and rear- 80 wardly, and is provided with apertures for the 85 passage of the screws or bolts C, which serve 45 to fasten the base to the foot, the lower or un- 50 der part of the latter being countersunk to re-

ceive the nuts on the bolts. The cushion- 50 spring a is, by preference, secured to one of said nuts. To the heads of the bolts are se- 55 cured the springs D, the function of which is to flexibly connect the foot and limb cup or 60 socket E. The said socket is of cylindrical 65 form, slightly tapering, and is adapted to re- 70 ceive and connect with the lower end of the 75 limb-section. At its lower extremity it is pro- 80 vided with a hub, e, projecting from which are 85 studs or pintles F, which enter apertures in 90 the journal-blocks B, and oscillate therein dur- 95 ing the act of walking.

Extending forwardly and rearwardly from 60 the socket E are lugs f, projecting from the 65 under side of which are studs G, to which the 70 upper ends of the springs D are secured. The 75 forward side of the socket is provided with a 80 vertical way, H, in which is adapted to slide 85 the upper end of the curved spring I, the lower 90 and forward end of which is secured to the 95 foot at about the point of the instep. This 100 spring is slotted at its upper portion, and is 105 held in the way H by means of the plate h, 110 which fits over the same, and the screw g, hav- 115 ing its point extended into the socket-wall.

It will thus be observed that a perfectly 120 flexible union of the foot and limb is secured, 125 and this with strength and simplicity.

Having thus fully described my invention, 130 what I claim as new, and desire to secure by 135 Letters Patent, is—

In an artificial limb, the combination, with 140 the foot provided with the fixed base-piece and 145 journal-blocks, and the cushion-spring, of the 150 socket journaled to the blocks, the springs in- 155 terposed and secured between and to the foot 160 and socket, and the curved slotted spring fast- 165 ened to the foot and working and held in the 170 way in the socket, substantially as described.

In testimony whereof I affix my signature in 175 presence of two witnesses.

JOSEPH FURRER.
